HUGO HAISS, OF ALLIANCE, OHIO, ASSIGNOR TO THE MORGAN ENGINEERING COMPANY,
OF ALLIANCE, OHIO.

HYDRAULIC VALVE.

1,233,052.

Specification of Letters Patent. Patented July 10, 1917.

Application filed June 8, 1916. Serial No. 102,419.

To all whom it may concern:

Be it known that I, HUGO HAISS, a subject of the Emperor of Germany, and a resident of Alliance, in the county of Stark and State of Ohio, have invented certain new and useful Improvements in Hydraulic Valves; and I do hereby declare the following to be a full, clear, and exact description of the invention, such as will enable others skilled in the art to which it appertains to make and use the same.

My invention relates to improvements in hydraulic valves, adapted particularly for use with presses for forging, punching, piercing, drawing, etc.

For the working manipulation of such hydraulic presses, accumulator water or water from a high pressure pumping plant is usually used, and it is the custom to regulate the supply and exhaust by means of three-way valves. For presses of large capacity, operated under high pressure water of 3,000 pounds per square inch or more, hand operated valves are difficult to operate, and slow in starting owing to the great power required to lift the valve from its seat. Another disadvantage of the three-way valve is that the exhaust water passage thereof, is of the same area as the inlet valve.

The object of this invention is to provide a valve which is actuated to open the port from the accumulator to the press cylinder, and from the press cylinder to the exhaust port by the pressure of the water from the accumulator, and it consists in the parts and combinations of parts as will be more fully explained and pointed out in the claims.

In the accompanying drawings, Figure 1 is a view in elevation of a press showing my improvement applied thereto. Fig. 2 is a view in vertical longitudinal section of the valve. Fig. 3 is a view in section on the line A—A of Fig. 2. Fig. 4 is a view in section on the line B—B of Fig. 2, and Fig. 5 is a view in section of a modified construction.

The press illustrated consists of a base 6; columns 7; sliding cross-head 8 guided by the columns; the press cylinder and top platen 9 secured to the upper ends of the columns; plunger 10 mounted in the cylinder and connected with the cross-head, and the pull-back cylinder 11, the plungers 12 of which are secured at their lower ends to the

cross-head. The pull-back cylinders are secured to the opposite sides of the top platen 9, and are preferably connected with the main hydraulic pressure line 13, and under the constant pressure so that the tendency of the pull-back cylinders is to maintain the cross-head 8 in its uppermost position, and thus operate to lift the same as soon as the pressure in the cylinder 9 against the main plunger or ram 10 is withdrawn.

In the form shown in the drawings my improved valve 14 is secured to the upper end of cylinder 9 and is in direct communication at its bottom with said cylinder.

This valve consists of a body 15 having two chambers or cylinders 14^a and 14^b; top cover 16; sliding piston 17 having a bored piston rod 18; the puppet valve 19 and spring 20. The valve body 15 and cover 16 are preferably made of gun iron or cast steel accurately bored and polished and provided with four ports. The upper port 21, leading from the cylinder 14^a above the piston 17, is connected by pipe 21^a to a three-way operating pilot valve 22, which has pipe connection 23 and 24 respectively with the hydraulic pressure line 13 and exhaust pipe 25. The port 26 connects with the main hydraulic pressure line, adjacent the bottom of the cylinder 14^a in which the piston 17 moves so as to discharge water under said piston. Port 27 leads to the press cylinder 9, and port 28 connects with the exhaust pipe 25, the said ports 25 and 27 being in communication with chamber 14^b. The piston 17 and hollow piston rod 18 are preferably made integral as shown, the piston being located in chamber or cylinder 14^a and the piston rod extending from cylinder 14^a to the chamber 14^b and constituting the sole medium of communication between the two. This piston and its rod are accurately guided, and are packed by hydraulic leather packings 29, in order to prevent leakage of the pressure water in either direction.

The piston 17 is hollow and is closed at its top by a bronze threaded nut 30, which acts as a guide for the valve 19 and a housing for the spring 20, a square section loose leather ring 31 being used as a packing to prevent the passage of any water under pressure up around the head 30. This piston is provided at the juncture of the latter with the piston rod 18, with a series of holes 32

for the passage of the pressure water, and is also provided with a series of holes 33 for the legs 34 of the valve chair 35. This valve chair 35 carries the valve 19 and is provided with a tubular extension to receive the lower end of the spring 20, the upper end of said spring embracing the lug 36 integral with the top 30 of the piston.

The valve 19 is of the puppet valve type and rests on a conical seat at the upper end of the piston rod, the latter, as shown being integral with the piston 17, with its bore in communication with the hollow piston. The valve 19 is therefore within the piston and normally operates to close the upper end of the bore of the piston rod.

The piston rod is packed intermediate the cylinder 14^a and chamber 14^b, as previously explained and its lower end is made conical 20 to engage the conical valve seat 37, at the upper end of port 27 leading to the press cylinder. From the foregoing it will be seen that port 21 which leads from the pilot valve opens into the cylinder 14^a above the piston 17; port 26 from the accumulator communicates with said cylinder below the piston, while port 27 leading to the press cylinder and exhaust port 28, communicates with chamber 14^b and has no connection with 25 the cylinder 14^a, except through the bore of the piston rod.

In the operation of the valve, water from the accumulator or other source of fluid pressure, is admitted through pipe 13 to port 35 26, and from the latter to the valve cylinder 14^a below piston 17, and operates to force and hold the valve 19 down onto its seat thus closing the bore through the piston rod, so as to prevent any pressure water from 40 entering the press cylinder, and elevates the piston 17 as shown in Fig. 2. This upward movement of the piston 17 and its rod 18, puts the port 27 to the press cylinder into communication with the chamber 14^b and 45 with exhaust port 28, so that any water in the press cylinder will be free to be forced out of the press cylinder and into said exhaust port and pipe 25 by the constant action of the pull-back cylinders. By now admitting water from the accumulator, through the three-way pilot valve to port 21 above the piston 17, the latter will be forced 50 downwardly, and will first shut-off the exhaust port 28 from the press cylinder port 27, and then open valve 19 by reason of the contact of the legs 34 of the valve chair, with the seat 38 through which piston rod 18 passes. This movement of the valve 19 opens communication between the cylinder 14^a, and the press cylinder, and by now admitting pressure water into the cylinder 14^a through port 26, it will pass under valve 55 19, through the bore of the piston rod and into the press cylinder and operate in the usual manner to force the cross-head down-

wardly. To open the valve to discharge the water from the press cylinder, the pilot valve is manipulated to open port 21. The pressure of water under the piston 17 will then force the latter upwardly during which movement the valve 19 will close and shut off the water from the press cylinder, and port 27 will be opened to port 28, so that the water in the press cylinder can be freely forced out by the pull-back cylinders.

In the construction shown in Fig. 5, the port 27^a leading to the press cylinder is at the side, and exhaust port 28^a is at the bottom of the valve body. With this construction the lower end 18^a of the piston rod is closed, and the latter is provided with side openings 18^b communicating with the bore of the piston rod for the passage of the water to the press cylinder when the piston rod is closing the exhaust port.

This latter construction is designed for use on the side instead of at the top of the press cylinder, where the total height of the press and valve would interfere with the work of overhead cranes, and is also designed for use on presses having horizontal press cylinders.

When the press water is admitted and discharged through a three-way valve, the exhaust water port of the latter is of the same area as the inlet valve or port. With my construction the exhaust port may be considerably larger than the area of the inlet valve, so that the water will be discharged from the press cylinder much more rapidly than it is admitted, thus permitting of the quick return of the cross-head, which is important for the rapid manipulation of the press.

It is evident that many slight changes might be resorted to in the relative arrangement of parts shown and described without departing from the spirit and scope of my invention. Hence I would have it understood that I do not wish to confine myself to the exact construction herein shown and described, except as required by the scope of the claims.

Having fully described my invention what I claim as new and desire to secure by Letters Patent, is:

1. A hydraulic valve for a press consisting of a casing, a piston and hollow piston rod in said casing, a valve for the end of the piston rod adjacent the piston, means for positively opening said piston rod valve when the piston rod is moved downwardly, a port leading to the valve chamber above the piston for the admission of water to move the piston downwardly, a port for pressure water leading to the valve chamber below the piston, a port adapted to communicate with a press cylinder and a discharge port in open communication with the port to the press cylinder when the piston 125

and its rod are elevated, and which is cut off from connection with said press cylinder when the piston rod is in depressed position.

2. A hydraulic valve for a press consisting of a casing, a piston and hollow piston rod in said casing, the said piston and its rod being suitably packed, a valve normally closing the opening at the upper end of the piston rod, means for opening said piston rod valve when the piston rod is depressed, a port leading to a press cylinder and in open communication with the bore of the piston rod, a discharge port closed by said piston rod when the latter is in its lowered position, a port leading to the piston chamber above the piston and a port for pressure water leading to the piston chamber below the piston, whereby when said piston is depressed the pressure water will pass through the piston rod to the press chamber port.

3. A hydraulic valve for a press consisting of a casing, a piston and hollow piston rod, a valve for normally closing the open upper end of the latter, a spring for yieldingly holding said valve to its seat, means for positively opening the valve when the piston rod is depressed, ports communicating with said casing respectively above and below the piston, and two ports communicating with said casing below the chamber or cylinder therein in which the piston moves, one of said latter ports communicating with the open bore of the piston rod, and the other adapted to be closed by the lower end of said piston rod when the latter is in its depressed position.

4. A hydraulic valve for a press consisting of a casing, a hollow piston and hollow piston rod, a valve for the upper open end of the piston rod, a spring for yieldingly holding said valve to its seat, a projection rigid with the valve and adapted to be engaged by a fixed stop for opening said valve when the piston rod is depressed, a port communicating with the piston chamber above the piston, a port communicating with the piston chamber below the piston, the piston having openings therein for the passage

of water below same to the hollow piston rod, a port leading from the valve casing to a press cylinder, the said port being in open communication with the bore of the piston rod, and a discharge port in open communication with said press cylinder port when the piston rod is elevated.

5. A hydraulic valve for a press consisting of a casing, a hollow piston and hollow piston rod in said casing, the said piston and rod being suitably packed, the piston having openings therein for the passage of water to the upper end of the hollow rod, a valve for closing the upper end of the bore of the piston rod, a spring yieldingly holding said valve to its seat, a projection from the valve adapted to engage a fixed stop for opening said valve when the piston rod is depressed, ports in the casing above and below the piston, a press cylinder port in open communication with the bore of the piston rod and an exhaust port communicating with the press cylinder port when the piston rod is elevated and its valve closed.

6. The combination with a pressure pipe, an exhaust pipe, a three-way pilot valve connected up with each, a valve casing, a piston and piston rod in said casing, the rod being hollow and open at its end, a valve for normally closing the upper open end of said hollow piston rod, a port connected with a pipe leading from the pilot valve to the valve casing above the piston in the latter, a port in said casing below the piston in communication with the pressure pipe, a port leading from the casing to the press cylinder and in open communication with the bore of the piston rod and an exhaust port in the casing connected with the exhaust pipe, the said exhaust port being closed when the piston rod is depressed.

In testimony whereof, I have signed this specification in the presence of two subscribing witnesses.

HUGO HAISS.
